UNITED STATES PATENT OFFICE.

JOHN H. MORAN, OF LICKING, MISSOURI.

ASH-LEACH.

SPECIFICATION forming part of Letters Patent No. 326,581, dated September 22, 1885.
Application filed October 26, 1883. (No model.)

To all whom it may concern:

Be it known that I, JOHN H. MORAN, a citizen of the United States, residing at Licking, in the county of Texas and State of Missouri, have invented a new and useful Improvement 5 in Ash-Hoppers; and I do hereby declare that the following is a full, clear, and exact description of the invention, which will enable others skilled in the art to which it appertains 10 to make and use the same.

My invention relates to improvements in ash-hoppers which are especially designed for leaching ashes in the process of making lye.

My objects are to combine with a sheet- 15 metal body of elongated form in cross-section a cast-metal floor having flanges to receive and hold said body and a tapered spout having side flanges, said body being provided with vent-holes that serve as hand-grips, and 20 also with a discharge-outlet of such shape that while it will retain the ashes in the hopper it will allow a free discharge of the lye to the spout, all of which will be fully understood from the following description, when 25 taken in connection with the accompanying drawings, in which—

Figure 1 is a side elevation of my improved ash-hopper. Fig. 2 is a vertical section taken through the hopper from front to rear. Fig. 30 3 is a front view of the hopper on a reduced scale, intended to show the peculiar shape of the discharge-passage. Fig. 4 is a top view, also on a reduced scale, of the cast-iron flanged bottom and its flanged discharge-spout.

35 In the annexed drawings, A designates the elongated bottom of the hopper, and A' the spout thereof. This bottom and its spout are cast in one and provided with broad flanges c c, as clearly shown in the drawings. The 40 shape (elongated) of the hopper insures a leaching of the entire mass of ashes. Were the said hopper round, the parts of the ashes not in line with the spout would in many instances not be wet by the water. The straight walls shown in Fig. 4 confine the ashes in such narrow limits that water poured in at the rear will wet all the ashes before it reaches the spout.

B designates the body of the hopper, which 50 is of the same elongated shape in cross-section as the bottom or floor A, so that these

parts will be rigidly held together without rivets.

The body A is provided with a tightly-fitting removable cover, C, having a lifting-handle, a. Just below the surrounding flange of the cover, at the ends of the body B, I make vent-apertures b b for the admission of air, for the purpose of allowing a free passage or percolation of the water and lye through the ashes contained in the body B. These apertures b b are made of such size and shape (shown in Fig. 3) that they not only serve as vents for air, but they also serve the additional purpose as hand holes or grips for 6: conveniently moving the hopper from place to place.

At the bottom B, and in line with the discharge-spout A', is the common discharge-outlet, E, for the lye. This outlet E is made 70 highest at the center e, and from this point it is gradually reduced in height, terminating at the points e' e', as shown in Fig. 3. The object of making the outlet of this shape is to resist in the best possible manner the 75 weight of the superincumbent ashes, and thus prevent the discharge of the same with the lye, at the same time to allow a free discharge of the lye.

I am aware that ash leaches or hoppers 80 have been made wholly of sheet metal before my invention, and lay no claim, broadly, to such devices.

Having described my invention, what I 85 claim is—

1. An ash hopper or leach consisting of a cast-metal bottom, A, formed with a spout and with flanges, in combination with a sheet-metal body, B, provided with a cover, and constructed with air-vents b b, that are adapted 90 to serve the additional function of hand-grips, and also with an outlet, E, of the form substantially as described.

2. An ash-leach consisting of a body and bottom of greater length than width, the bottom being provided with a spout, substantially as and for the purpose specified.

JOHN H. MORAN.
